UNITED STATES PATENT OFFICE.

FREDERIK NIELSEN, OF EPPING, NEAR SYDNEY, NEW SOUTH WALES, AUSTRALIA.

VULCANIZER FOR RUBBER SOLES TO UPPERS.

Application filed April 26, 1928, Serial No. 273,107, and in Australia June 17, 1927.

This invention relates to improvements in machines for vulcanizing rubber soles to fabric uppers of boots or shoes.

In the manufacture heretofore of this class of boot or shoe, various methods have been adopted, one of which was to employ a flexible rubber bag on which the upper was mounted. By this method the upper presented an irregular shape, and when placed in position and the shoe mould closed, was obscured from view. Consequently any creases, which frequently occur, cannot be smoothed out by inflating the bag; and the raw rubber from which the sole is to be formed frequently extends beyond the sole top ridge, adhering to the sides of the upper and leaving an unsightly appearance.

It has also been suggested to present the boot or shoe to the sole mould upon the same last as that on which it was first mounted for lasting and to apply internal heat to the boot or shoe for the purpose of vulcanization.

It has further been proposed to place the boot or shoe upper with its insole secured thereto, upon the last of a vulcanizing machine; with the upper downwards and then reverse the last and its attached upper, so as to bring the latter into engagement with the sole mould on the machine before admitting steam to a vulcanizing chamber attached to the last.

The object of the present invention is to effect improvements in vulcanizing machines of the latter type and particularly to devise means whereby internal vulcanization is carried out more rapidly and effectively, and creasing of the upper is obviated.

The improved machine may have a single vulcanizing last and associated parts, or a suitable number of lasts may be grouped to form a unit.

The method of manufacture in the improved machine consists of a combination of two methods, namely:

(1) The solutioning or securing of the shoe uppers to an insole on a separate last, as in hand made shoes, and accumulating them in readiness to be placed on a machine last as soon as the same is vacant.

(2) The placing of a sole of vulcanizable rubber on the solutioned upper or the placing of sole rubber in the open mould before the upper mounted on the machine last is lowered onto the mould and pressure and heat applied simultaneously to the internal

vulcanizer last before vulcanization takes place.

According to the present invention I provide a vulcanizer having space provided therein for steam, which is supplied from an external source, such as a boiler, provision being made for the escape of the water of condensation. This vulcanizer is pivoted to a supporting frame or legs and is capable of being rotated through an angle of approximately 180°.

A combined internal vulcanizer and last is provided for use in conjunction with the vulcanizer and is also capable of being rotated through 180° with the object of withdrawing the water of condensation; such water may be removed from one or both of the vulcanizers in their reversed position and if desired steam traps or other interceptor means may be provided.

The necessary pressure exerted by the last upon the insole may be provided by screwed connections and/or levers between or on the top of the last, and the vulcanizer casting, such as right and left hand threaded screws whereby the desired pressure is obtained upon the rubber compound from which the sole is to be made. Internal vulcanization may also be accomplished by means of an electrically heated element of normal construction, and taking the place of the steam in the internal vulcanizer.

Pressure and heat is imparted from the combined internal vulcanizer and last by means of a metal insole which may be in two parts hinged to bridge the space between the heel and fore part of the last, and is situated between the lower face of the internal vulcanizer and the insole of the boot or shoe, heat being imparted through the canvas or other structure to the rubber forming the sole.

Provision is also made whereby it is possible to detach or adjust the combined internal vulcanizer and last or any part thereof without disconnecting its operating links or mechanism. If desired the front part of the last may be detachable from the heel portion.

The necessary glands and stuffing boxes are provided so as to permit free movement of the vulcanizer.

Lever operated mechanism is provided for reversing the position of the combined internal vulcanizer and last apart from the reversing of the vulcanizer.

Broadly speaking the last consists of three main parts, namely a movable heel part, a fore part, and a metal insole. Taken as a whole, it is a rigid non-flexible body. 5 Its chief functions are to carry the shoe structure, to convey heat whereby internal vulcanization may take place; and to act as a medium whereby pressure may be applied during vulcanization onto the rubber compound forming the sole. 10

The metal insole figuratively enters the cavity of the mould, when the final pressure has been applied to the last, but the last may be lowered still further in accordance 15 with the quantity of vulcanizable rubber placed in the mould. The extent of variation is slightly less than the thickness of the metal insole.

If desired the metal insole may be made 20 of thin steel plate, to the underside of which is attached a heavier gauge aluminium plate. The steel plate would be made an easy fit in mould cavity, and the aluminium plate a somewhat neat fit. The 25 aluminium has the advantage that it will not cut the shoe structure, and if it is binding in places, it will slightly compress the first time, and always make a perfect joint afterwards. The insole may be attached to 30 the last so as to remain attached when the shoe structure is removed from the last.

Pressure is applied to the lever supporting the last by means of an eccentric hand lever. This latter lever brings the last down into 35 close contact with a vulcanizable sole with only a slight amount of exertion. A further and final pressure is applied by adjusting a right and left hand screw by means of a correspondingly screwed sleeve with an 40 adjustable handle attached thereto, until the mould is observed to slightly open, indicating that it is full. When once the position of the handle has been determined for a particular thickness of sole, all that is necessary 45 is to place the handle in that position in subsequent operations.

An eccentric hand lever on the last supporting lever has a safety detent adapted to engage a notch, to prevent the hand lever 50 from being accidentally knocked out of place during the application of pressure to the vulcanizer.

The vulcanizer is cast in one piece with suitable stay ribs, and is pivotally mounted 55 upon a frame or support.

Steam is admitted to both the vulcanizer body and the internal vulcanizer, through glands and stuffing boxes, the purpose of which is to facilitate the turning of the respective parts, through approximately 180 degrees to enable condensed steam to drain away and to facilitate the placing of the shoe upon the last.

A locking pawl with a conveniently

placed releaser lever has been affixed on the stand. Its functions is to hold the rotatable vulcanizer and associated parts rigid when not required to be revolved.

A balance weight is placed in a suitable position on the vulcanizer so as to minimize 70 the normal exertion required in revolving the same.

The vulcanizer body may be suitably insulated, the only exposed part being the upper surface or hot plate. Consequently 75 steam is consumed practically only during vulcanization.

Mould plates which are slidable, rest on the hot plate of the vulcanizer and are built up in sets according to sizes of boots or 80 shoes desired to be made. In cool climates the moulds may be steam jacketed. To each mould plate a steel plate is secured so as to overhang the edge of the mould and make a close joint all around the shoe upper. A 85 metal sole plate is provided to form the bottom of the mould.

But in order that the invention may be more readily understood, reference will now be made to the accompanying drawings 90 wherein:—

Figure 1 is an elevation of the left hand side of the improved machine.

Figure 2 is an elevation of the right hand side thereof. 95

Figure 3 is a part and elevational view of the machine shown in Figures 1 and 2.

Figure 4 is a side view showing the vulcanizer and its associated parts reversed upon its pivot to permit the water of condensation to drain out. 100

Figure 5 is a plan view of the sliding mould plates showing the racks and pinions by which they are opened and closed.

Figure 6 is a section on the line 6—6 of 105 Figure 5.

Figure 7 is a plan view of a sole plate adapted to impart configuration to the sole while it is in the mould.

Figure 8 is a detail view showing the 110 means for locking the vulcanizer and associated parts against rotation, on its pivots.

Figure 9 is an elevational view partly in section showing the internal vulcanizer last on an enlarged scale. 115

Figure 10 is an elevation of a metal insole plate for use therewith.

Figure 11 is a diagrammatic sectional view showing the toe end of the last, in association with the mould. 120

Figure 12 is an elevation on an enlarged scale showing a universally pivoted link for connecting a hand lever with quadrants for operating the moulds.

The vulcanizer 15 with its associated parts 125 is mounted in bearings 16 on the machine frame 17. This frame may be extended to take as many vulcanizer units as desired.

The whole of the operating parts are carried by the vulcanizer and are rotatable therewith as indicated in Figure 4.

The steam is admitted to the vulcanizer 5 through one bearing, stuffing boxes 18 of ordinary construction being provided between the fixed and the rotating parts of the bearings. A balance weight 19 is provided so that the machine will turn evenly 10 upon its bearings.

The vulcanizer 15 has an extension at the rear thereof to which is adjustably secured a vertical member 20, the adjustability being effected by a pivoted arm 21 which 15 passes through the end of the member 20 and clamps it between two nuts 22.

A hollow pivot 23 is secured to the vertical member 20 and loosely supports an arm 24 see Figure 1, and a last supporting lever 20 25. The lever 25 is free to rise upon the pivot 23 when actuated by the cord 26, as will be explained later, but is maintained in its normal horizontal position by the engagement of a stop 27, with a stop 28 attached to the arm 24.

The last supporting lever 25 is held during vulcanization by an eccentric hand lever 29 which has a safety detent 30 engaging a 30 notch in the lever 25 and is locked by a spring pressed catch 31. The eccentric hand lever 29 applies pressure to the last supporting lever 25 and brings the last down into close contact with the vulcanizable sole, final adjustment being effected by right and 35 left hand screws 32, 33, and a correspondingly screwed sleeve with an adjustable handle 34.

To the lower end of the arm 24, one end of a coiled spring 35 is secured, the other end 40 of the spring being anchored to a bracket 36 projecting from the bottom of the vulcanizer body 15.

The lower end of the arm 24 has also 45 connected to it a rod 37 adapted to slide in a bracket 38 depending from the vulcanizer 15. This rod 37 carries an adjustable flanged collar 39 adapted to be engaged by a bell crank lever 40 pivoted upon a bracket 41 forming part of the machine frame 17. 50 The bell crank lever 40 is connected by a rod 42 to a foot lever 43 also pivoted to the machine frame 17.

The action of the spring 35 upon the arm 55 24 tends to raise the last supporting lever 25 clear of the mould when the latter is not held down by the eccentric hand lever 29. The foot lever 43 bell crank lever 40, and the rod 37 serve to take the load off the spring, and enable the last supporting lever 60 and its associated parts to descend by their own weight and allow the eccentric hand lever 29 to be placed in position.

The vulcanizer 15 and its associated parts are capable of being reversed upon the bearings 16 with the assistance of the hand lever

29, and a handle 44 but is normally held in the position shown in Figure 1 by the engagement of a stop 45 on the vulcanizer with a catch 46 pivoted on the frame 17. When it is desired to reverse the vulcanizer 70 upon its bearings to the position shown in Figure 4 the catch 46 is removed from the stop 45 by means of a rod 47 and hand lever 48.

A combined internal vulcanizer and last, 75 see Figures 9 and 10 is pivoted to the last supporting lever 25 and is maintained in an approximately level position by a slotted link 49, spring 57 and a coupling rod 50. The combined internal vulcanizer and last 80 consists of a movable heel part 51, a fore part 52 and a metal insole 53.

The fore part of the last as shown in Figure 9 is hollowed to receive steam and has an extension 54 to which the movable heel 85 part is pivoted. The said heel part 51 is under the action of a spring 55 when folded up, and is adapted to be extended by a hand lever 56. The metal insole 53 which may be made of hinged parts as shown in Figure 90 10 is placed between the last and the insole of the shoe. The metal insole 53 serves the purposes of permitting a variable parallel movement of the last, bridging the gap between the heel part and the fore part, and of 95 evenly distributing heat and pressure to the insole of the shoe.

Mould plates for shaping the sole rest on the upper surface or hot plate of the vulcanizer 15 and are made in sizes to suit the work in hand. To the mould plates 58 a steel plate 59 is secured. This slightly overhangs the edge of the mould plates 58 and makes a close point all round the shoe upper and against a metal insole 53. A metal sole plate 60 forms the bottom of the mould. The steel plate 59 in conjunction with metal insole 53 prevents the raw rubber from creeping onto the surface of the upper. Between the steel plate 59 and guide plates 11 105 a sheet of insulating material 62 is placed.

Each mould section has holding down blocks and is provided with racks 63 adapted to be engaged by pinions 64 mounted on shafts 65 and simultaneously operated by toothed quadrants 66, from a hand lever 67 pivoted to an arm 68 extending from the vulcanizer 15, and having a stop 69 for engagement by a pawl 70 on the hand lever 67. The bearings 71 are split and the moulds may be changed by removing all top gears in one piece. A universally pivoted link 72 is provided to connect the hand lever 67 with one of the toothed quadrants 66.

To enable the last supporting lever 25 and the parts carried thereby to be rotated through approximately 180° mechanism, such as a pull operated lever 73 and cord 26, is provided. The uppers of the boots or 130

shoes to be soled are made in the usual way and have an insole secured thereto by rubber solution, or other approved means to form what I will call a shoe body. The metal insole 53 if not previously attached to the last is inserted in the shoe body so that the latter is ready for placing upon the last.

In commencing the operation of vulcanizing a sole upon the shoe body, the last 10 and its supporting arm are turned through approximately 180° from the position shown in Figure 1, by means of the pull operated lever 73, the cord 26 serving to steady the lever 25 on each side of the dead centre.

15 When the last is in the position just described a shoe body is placed thereon, the pull operated lever is again operated to bring the shoe body into position above the previously closed and filled mould 58.

20 The foot lever 43 is depressed allowing the last supporting lever 25 and last to descend by their own weight so that the inner sole engages with the rubber compound from which the sole is to be formed. The hand lever 29 is placed in position and final pressure applied by means of the screwed handle 34.

25 The lever 48 is now operated to release the catch 46 from the stop 45 and permit the reversal of the machine upon its bearings 16 into the vulcanizing position, when steam is admitted to the internal vulcanizer, see Figure 4. During vulcanization water of condensation can pass away from the vulcanizer 15, and the last, owing to both being in a reversed position. The inlet and outlet of steam to the vulcanizer 14 is effected through the stuffing boxes 18 in the pivot bearings 16. A stuffing box 74 is also 30 formed on the hollow pivot 23 to enable steam to be conducted to the last 52. The inlet and discharge ports for the last are indicated in Figure 9 by the numerals 75 and 76.

45 After vulcanization the machine is returned to the position shown in Figure 1 whereupon the shoe is removed and the machine left ready for a fresh operation.

I claim:

50 1. In a vulcanizing machine of the kind described, the combination with a horizontally pivoted vulcanizer, of a heated last, moulds for use therewith and means for bringing said last and moulds into position 55 for simultaneous vulcanization inside and outside the shoe.

2. In a vulcanizing machine of the kind described, the combination with a vulcanizer horizontally pivoted to the machine frame, of an internally heated last mounted upon a last supporting lever horizontally pivoted, and capable of being rotated through approximately 180°, moulds for use with said last, and means for opening and closing said moulds.

3. In a vulcanizing machine of the kind described, the combination with a vulcanizer, of a metal insole, an internal vulcanizing last, moulds for use therewith and means for reversing the positions of the said vulcanizer and last to remove water of condensation therefrom.

4. In a vulcanizing machine of the kind described, the combination with a horizontally pivoted vulcanizer, of a heated last mounted upon a last supporting lever capable of being turned through approximately 180°, an eccentric hand lever and right and left hand screws and handle for applying downward pressure to said last supporting lever, moulds for use with the last, and means for opening and closing the moulds.

5. In a vulcanizing machine of the kind described the combination with a horizontally pivoted vulcanizer, of a heated last mounted upon a last supporting lever, a coiled spring and arm for supporting said last supporting lever, and means for operating the arm against the action of the coiled spring so as to permit the last supporting lever and associated parts to descend under their own weight, moulds for use with the last, and means for opening and closing the moulds.

6. In a vulcanizing machine of the kind described, the combination with a horizontally pivoted vulcanizer, of a heated last mounted upon a last supporting lever, a coiled spring and arm for supporting the last supporting lever, a sliding rod connected to said arm and having a flanged collar adapted to be engaged by a bell crank lever, a rod and foot lever for operating the bell crank lever to operate the arm against the action of the coiled spring so as to permit the last supporting lever and associated parts to descend under their own weight, moulds for use with the last, and means for opening and closing the moulds.

In testimony whereof I have hereunto set my hand.

FREDERIK NIELSEN.
